CLAIM

I claim, the ornamental design for hanging lamp, as shown and described.

DESCRIPTION

FIG. 1 is a front and top view of the hanging lamp showing my new design;

FIG. 2 is a front and bottom view thereof;

FIG. 3 is a bottom plan view thereof;

FIG. 4 is a rear view thereof;

FIG. 5 is a side view thereof;

FIG. 6 is a front and top view of the hanging lamp showing my new design with the parts shown positioned in a first alternate configuration;

FIG. 7 is a side view of the configuration shown in FIG. 6;

FIG. 8 is a top plan view of the configuration shown in FIG. 6;

FIG. 9 is a front and top view of the hanging lamp showing my new design with the parts shown positioned in a second alternate configuration;

FIG. 10 is a top plan view of the configuration shown in FIG. 9;

FIG. 11 is a side view of the configuration shown in FIG. 9;

FIG. 12 is a front and top view of the hanging lamp showing my new design with the parts shown positioned in a third alternate configuration;

FIG. 13 is a top plan view of the configuration shown in FIG. 12; and,

FIG. 14 side view of the configuration shown in FIG. 12.
